UNITED STATES PATENT OFFICE.

WILLIAM VANSKOYOE, OF OXFORD, OHIO.

DESIGN FOR A HAT-RACK AND MIRROR.

Specification forming part of Design No. 5,233, dated August 21, 1871.
[Term of Patent 7 years.]

To all whom it may concern:

Be it known that I, WILLIAM VANSKOYOE, of Oxford, in the county of Butler and State of Ohio, have invented a new and useful Design for Combined Hat-Rack and Mirror; and I do hereby declare the following to be a full clear, and exact description thereof, reference being had to the accompanying drawing, forming a part of the same, and in which is illustrated a perspective view of my improved design for combined hat-rack and mirror.

This invention has reference to an improved design for a combined hat-rack and mirror; and it consists of the parts thereof constructed and arranged in the manner as hereinafter more fully described and claimed.

To enable others to make and use my invention I will proceed to describe it.

In the annexed drawing, the frame A A, consisting of a series of bars or slats crossing each other, is of a diamond shape, as plainly illustrated therein, and is supplied at the points of intersection between its bars with segmented pins or racks B B, upon which

the hat or other article of wear may be deposited, and between the center ones of which pins is placed the mirror C, the latter being held in place simply by the pressure of said pins against its sides, as plainly shown.

The pins B B are of such a shape as to form recesses at their lower ends or bases, which receive the frame of the mirror C, thereby assisting the holding of the said mirror in its place.

Having thus described my invention, what I claim, and desire to secure by Letters Patent, is—

The design, substantially as herein described and shown, for a combined hat-rack and mirror.

In testimony whereof I have hereunto signed my name this 1st day of August, A. D. 1871, in presence of two subscribing witnesses.

WILLIAM VANSKOYOE.
